UNITED STATES PATENT OFFICE.

FRANK S. HYATT, OF BROOKLYN, NEW YORK.

DESIGN FOR A POWDER-CONTAINER TOP.

58,909.

Specification for Design.

Patented Sept. 6, 1921.

Application filed February 8, 1921. Serial No. 443,476. Term of patent 3½ years.

To all whom it may concern:

Be it known that I, FRANK S. HYATT, a citizen of the United States, residing at Brooklyn, in the county of Kings and State of New York, have invented a new, original, and ornamental Design for Powder-Container Tops, of which the following is a specification, reference being had to the accompanying drawings, forming part thereof, in which—

Figure 1 is a top plan view of a powder container top showing my design.

Fig. 2 is a side elevation of the same.

I claim:

The ornamental design for a powder container top, as shown.

FRANK S. HYATT.
